(57) **CLAIM**

The ornamental design for a grease gun holder, as shown and described.

DESCRIPTION

FIG. 1 is a top right perspective view of a grease gun holder showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view thereof, shown in an example environment with a grease tray mounted to the grease gun holder; and,

FIG. 9 is a bottom right perspective view thereof, shown in an example environment with a grease tray mounted to the grease gun holder.

The broken lines shown in the figures represent portions of the grease gun holder that form no part of the claimed design.

The broken lines showing an example grease tray in FIGS. 8-9 are for the purpose of illustrating an environmental structure and form no part of the claimed design.
